LIGHTER

Bernhard Köllisch, Nornenstrasse 20, Nurnberg,
Bavaria, Germany

Filed Apr. 17, 1961, Ser. No. 64,768

Term of patent 7 years

(Cl. D48—27)

FIG-3

FIG-4

FIG-5

FIG-6

FIG-7

FIG. 1 is a perspective view of a lighter embodying my new design.

FIG. 2 is a perspective view thereof as seen from the right of FIG. 1.

FIG. 3 is a side elevation thereof.

FIG. 4 is an end elevation thereof as seen from the left of FIG. 3.

FIG. 5 is an end elevation thereof as seen from the right of FIG. 3.

FIG. 6 is a top plan view thereof.

FIG. 7 is a bottom plan view thereof.

The side of the lighter not shown is substantially the same in appearance as the side shown.

I claim:

The ornamental design for a lighter, as shown and described.
